Primary Examiner — Ricky Pham(74) *Attorney, Agent, or Firm* — Rumit R. Kanakia(57) **CLAIM**

The ornamental design for a meat cleaver, as shown and described.

DESCRIPTION

FIG. 1 is a front elevational view of a meat cleaver showing my new design;

FIG. 2 is a rear elevational view thereof; and

FIG. 3 is a left elevational view thereof;

FIG. 4 is a right side view thereof;

FIG. 5 is a top side view thereof;

FIG. 6 is a bottom plan view thereof; and,

FIG. 7 is a perspective view of a meat cleaver showing my new design.

The broken lines in the figures are for the purposes of illustrating portions of the meat cleaver, which form no part of the claimed design.
